US0D1077778S

(12) **United States Design Patent** (10) Patent No.: **US D1,077,778 S**
(45) Date of Patent: ** Jun. 3, 2025

(54) **LOUDSPEAKER**

(71) Applicant: **Pequod Acoustics S.r.l.**, Florence (IT)

(72) Inventors: **Andrea Ugolini**, Fiesole (IT);
Alessandro Genovese, Pisa (IT)

(73) Assignee: **PEQUOD ACOUSTICS S.R.L.**,
Florence (IT)

(**) Term: **15 Years**

(21) Appl. No.: **35/519,804**

(22) Filed: **Jan. 26, 2023**

(80) **Hague Agreement Data**

Int. Filing Date: **Jan. 26, 2023**

Int. Reg. No.: **DM/227721**

Int. Reg. Date: **Jan. 26, 2023**

Int. Reg. Pub. Date: **Jan. 26, 2024**

(51) **LOC (15) Cl.** **14-01**

(52) **U.S. Cl.**

USPC **D14/216**
